US0D1099634S

(12) **United States Design Patent** (10) **Patent No.:** **US D1,099,634 S**
(45) **Date of Patent:** **** Oct. 28, 2025**

(54) **MIST BOTTLE WITH HANDLE**

(71) Applicant: **STOR, S.L.**, Madrid (ES)

(72) Inventor: **Valentin Ortiz Gispert**, Madrid (ES)

(73) Assignee: **STOR, S.L.**, Madrid (ES)

(**) Term: **15 Years**

(21) Appl. No.: **29/854,960**

(22) Filed: **Sep. 29, 2022**

Related U.S. Application Data

(62) Division of application No. 35/512,597, filed on May 11, 2021 (U.S. filing date under 35 U.S.C. 384), and having an international filing date of May 11, 2021, now Pat. No. Des. 1,032,293.

(57) **CLAIM**

The ornamental design for a mist bottle with handle as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view, showing the new design for a mist bottle with handle;

FIG. 2 is a left side elevational view;

FIG. 3 is a front elevational view;

FIG. 4 is a right side elevational view;

FIG. 5 is a rear elevational view;

FIG. 6 is a top plan view; and,

FIG. 7 is a bottom plan view thereof.

The portions of the mist bottle with handle shown in broken lines form no part of the claimed design.

1 Claim, 6 Drawing Sheets
